ALMOND SHELLING MACHINE

Willard F. Smith, Brooks, Calif.

Application January 11, 1947, Serial No. 721,550

3 Claims. (Cl. 146—11)

1

This invention is directed to, and it is an object to provide, an improved almond shelling machine of the type which includes a rotor turning in spaced, eccentric relation within a rotary, foraminous cylinder; the cooperative action of the rotor and cylinder on the almonds effecting the desired cracking and shelling thereof.

Another object of the invention is to provide an almond shelling machine, as above, including a novel adjustable mount for the foraminous shelling cylinder, whereby said cylinder may be set to run, with such selected spacing from the rotor, as working conditions may require.

A further object of the invention is to provide an almond shelling machine which includes a drive mechanism operative to impart like-direction but differential speed to the cylinder and rotor; the rotor traveling faster than the cylinder, which facilitates the shelling operation.

An additional object of the invention is to provide an almond shelling machine designed for ready access to the working parts so as to make it easy to clean and service the same.

A further object of the invention is to provide an almond shelling machine which is practical, and one which will be exceedingly effective for the purpose for which it is designed.

These objects are accomplished by means of such structure and relative arrangement of parts as will fully appear by a perusal of the following specification and claims.

In the drawings:

Fig. 1 is a cross section of the improved almond shelling machine.

Fig. 2 is a longitudinal sectional elevation of such machine.

Fig. 3 is a fragmentary cross section on line 3—3 of Fig. 1.

Fig. 4 is a fragmentary top plan view of the lever and linkage assembly employed to adjust the cylinder.

Referring now more particularly to the characters of reference on the drawings, the improved almond shelling machine comprises an upstanding main frame, indicated generally at 1, which frame includes rigid corner posts 2. At opposite ends of the main frame 1 there is provided upstanding end plates, indicated at 3 and 4, respectively, said end plates 3 and 4 being supported at one side, adjacent but short of the top, by a horizontal, longitudinally extending shaft 5 journaled adjacent opposite ends of the machine, in connection with corresponding corner posts 2. As thus mounted, the plates 3 are vertically swingably or pivotally supported for

up or down adjustment about the shaft 5 as an axis.

The end plates 3 are connected together in rigid relation by opposed, longitudinally extending baffles 6 which form, in effect, a trough 7 extending lengthwise of the machine. This trough is open at the bottom and communicates with a downwardly and laterally outwardly inclined discharge spout 8 movable with the end plates 3 as a unit.

The assembly of the end plates 3 and 4, and baffles 6, is vertically adjustably suspended on the side opposite the shaft 5 by a pair of links 9 which pivotally connect, at their lower ends, as at 10, to the end plate 3, and thence extend upwardly adjacent the corresponding corner posts 2. At their upper ends the links 9 pivotally connect, as at 11, to a radial lever 12 fixed on a stub shaft 13 extending horizontally through said corresponding corner post. To the side of the post opposite the lever 12 the stub shaft 13 is fitted with a radial hand lever 14. A nut 15 on the outer side of the hub of the hand lever 14 and friction washers 16 on the inner side are employed to normally clampingly engage the shaft 13 against rotation, whereby to maintain a selected position of vertical adjustment of the assembly of the end plates 3 and 4, and the trough forming baffles 6.

By loosening the nut 15 slightly, the hand lever 14 can be operated to effect vertical adjustment of such assembly, whereupon the nut 15 is tightened to lock up the parts.

A relatively large-diameter almond cracking cylinder 17 is disposed in the trough 7, and extends full length thereof between the end plates 3 and 4; the latter end plate including a removable portion 18 which provides, when removed, for ready access into the machine from said end.

The cylinder 17 is foraminous and is comprised of a plurality of circumferentially spaced, longitudinally extending bars 19 fixed, at opposite ends, to circular end rails 20. The end rails 20 run on transversely spaced supporting rollers 21 mounted in the bottom of the trough 7 on longitudinal shafts 22. Between the rollers 21 the shafts 22 are enclosed in sleeves 23 formed as part of the corresponding baffles 6.

The described cylinder 17 is held down, in its position on the supporting rollers 21, by top or hold-down rollers 24 riding the end rails 20 and carried on spring-urged arms 25 which radiate from a longitudinal shaft 26. The arms 25 are urged downwardly by a spring 27. The

longitudinal shaft 26 is fitted with a hand lever 28 whereby the arms 25 and the hold-down rollers may be swung upwardly to clear the rails 20, as is necessary when it is desired to remove the cylinder 17 from the machine. The shaft 5 is driven from any power source (not shown), and intermediate the end plates 3 and 4 is fitted with a sprocket 29 driving an endless chain 30 which extends about, and runs in mesh with, a ring gear 31 on the cylinder 17 intermediate its ends. In this way the cylinder 17 is rotated in the direction shown by the arrow in Fig. 1

A relatively small-diameter cracking rotor 32 is disposed in the cylinder 17 in eccentric relation toward one side of the latter adjacent the bottom thereof; said rotor 32 being formed at the ends with supporting hubs 33 secured on a stub shaft 34 journaled in connection with a cross member 35 and projecting into the cylinder 17 for engagement in said hubs. The shaft 34 is driven from the drive shaft 5 by an endless chain and sprocket unit 36.

While the cylinder 17 and rotor 32 turn in the same directions, the drive arrangements are such that said rotor 32 travels at much greater speed than the cylinder 17.

The rotor 32 is solid faced and includes, on said face, a plurality of circumferentially spaced, longitudinally extending ribs 37.

At the point where the stub shaft 34 projects through the end plate 3, the latter is slotted, as at 38, whereby to permit of up-or-down adjustment of the cylinder 17, by manipulation of the hand lever 14 in the manner previously described; the rotor 32 being non-adjustable. By up or down adjustment of the cylinder 17, the working gap 39 between said cylinder and the rotor 32 may be selectively varied as working conditions may require.

A hopper 40 at one end of the machine delivers to a chute 41 which leads through an opening 42 in end wall 3, whereby almonds can be fed into said cylinder 17 when the machine is in operation. With the machine operating and almonds fed thereinto, the latter are effectively cracked and shelled as they pass through the working gap 39 between the ribs 37 of said rotor 32 and the bars 19 of the cylinder 17. As the almonds are cracked and shelled they work between the bars 19 and fall into the discharge spout 8 for carry-off to a suitable receiver (not shown).

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. An almond shelling machine comprising an upstanding main frame, a foraminous cylinder, a rotor of smaller diameter within the cylinder and journaled on the frame, the rotor being eccentric relative to and adjacent one side of the

cylinder and spaced therefrom to form a nut-feed gap, power means to rotate the cylinder and rotor at relatively different and predetermined speeds, end plates on which the cylinder is supported for rotation, the end plates being pivoted adjacent one upper corner to the main frame, links pivoted to the lower corner of one of the end plates on the side thereof opposite the side on which such plate is pivoted to the main frame, and lever means connected to said link and operable through said link to swing the plates up and down to effect movement of the cylinder relative to the rotor to adjust the size of the gap between the two.

2. An almond shelling machine comprising a frame structure, a foraminous rotary cylinder, a relatively small diameter rotor within the cylinder in eccentric relation thereto, means mounting the cylinder and rotor on the frame structure for relative adjustment to alter the width of the space between the cylinder and rotor, and means to effect such adjustment and maintain the cylinder and drum set in any adjusted position.

3. An almond shelling machine comprising a main frame, a drive shaft journaled therein, end plates turnable on the shaft, a foraminous cylinder rotatably mounted on the plates, a relatively small diameter rotor disposed within the cylinder in eccentric relation thereto, a shaft on which the rotor is fixed, journaled in the main frame and projecting through an arcuate slot in one end plate, said slot being concentric with the shaft, the axes of the drive shaft, cylinder and rotor shaft being parallel, a chain drive connecting the drive shaft and cylinder between the end plates, a similar drive connecting the drive shaft and rotor shaft outwardly of said one end plate, and controlled means applied to the end plates to swing the same about the drive shaft.
